INVENTOR.

BY

Horace T. Thomas

Raymond A. Parker

ATTORNEY.

UNITED STATES PATENT OFFICE.

HORACE T. THOMAS, OF LANSING, MICHIGAN.

AUTOMOBILE CURTAIN.

Application filed April 5, 1923. Serial No. 629,957.

To all whom it may concern:

Be it known that I, HORACE T. THOMAS, a citizen of the United States, residing at Lansing, county of Ingham, State of Michigan, have invented a certain new and useful Improvement in Automobile Curtains, and declare the following to be a full, clear, and exact description of the same, such as will enable others skilled in the art to 10 which it pertains to make and use the same, reference being had to the accompanying drawings, which form a part of this specification.

My invention relates to curtains for automobiles and the method of constructing the same.

In the accompanying drawings,—

Figure 1 is a side elevation of a part of an automobile showing the curtains adjusted 20 thereto embodying my invention.

Fig. 2 is a detail section to an enlarged scale on the line II—II, Fig. 1.

Fig. 3 is a section to an enlarged scale and partly broken away, on the line 25 III—III, Fig. 1.

Fig. 4 is a detail section of the upper edge of the curtain as it is constructed preparatory to assembling the parts, forming the attaching means therefor.

Fig. 5 is a section of the strengthening 30 piece for the upper edge of the curtain.

Fig. 6 is a section of the upper edge of the curtain as assembled and ready for adjustment to place.

Fig. 7 is a detail elevation partly broken away illustrating the construction of the parts and the method of adjusting the curtain in position.

a is the body of the automobile and *a*² 40 the top thereof. *a*³ indicates the side rail of the top at one edge thereof. *b* is a curtain. *c* is a strip of suitable material having one edge looped and sewed as indicated at *c*² and having a cord *c*³ enclosed in said 45 loop, the loop and cord forming a welt for the lower edge of the strip *c*. Said strip is secured to the inner surface of the rail *a*³, the welt at the lower edge thereof being located just below the inner edge of said 50 rail as shown in Fig. 2.

The curtain *b* is turned over at its upper edge to form an elongated loop in cross-

section *b*² (Fig. 4) and is preferably folded and is secured as indicated at *b*³.

d is a metal strengthening strip formed 55 into a circular shape having a portion less than a semicircle broken away at its top in cross-section, as indicated in Fig. 5, so as to form a trough-like construction. The strip *d* is turned over at its edges at *d*² *d*³.

The trough *d* is inserted in the loop *b*² with its open part upward and the upper part of the loop *b*² is then pressed downward and into the trough of the strip *d*, as shown at *b*²*a*, Fig. 6, and is secured by 65 cementing to said strip. As thus formed the upper edge of the curtain is adapted to slide over an end of the welt *c*² *c*³ as indicated in Fig. 2 so as to make a tight connection between the curtain and the strip *c*. 70 The curtain may be slid along the welt as indicated in Fig. 7 to the position required.

e is a door. *e*² is a curtain carried by a frame above said door. The curtain *e*² when 75 the door *e* is closed engages against the welt *c*³ forcing the same slightly inward and forming a tight joint as indicated in Fig. 3.

What I claim is:

1. The combination of a vehicle top having 80 a side rail, a strip of flexible sheet material having a welt along one of its edges, said strip being secured to said rail so as to position said welt along the lower edge thereof, and a curtain having a trough-like construction at its top adapted to engage over said welt, and slide along the same for the purpose described.

2. The combination of a vehicle top having 90 a side rail, a strip of flexible sheet-material having a welt along one of its edges, said strip being secured to said rail so as to position said welt along the lower edge thereof, and a curtain having a trough-like construction at its top adapted to engage over 95 said welt and slide along the same for the purpose described, said construction consisting of a strip of rigid material extending along the curtain top.

3. The combination with an automobile 100 top, of a flexible valance depending from the edge of said top and having a welt along its lower edge, a curtain adapted to engage and slide along said welt, a door, a curtain

carried above said door, the last named curtain being adapted to engage against said welt to form a tight joint.

4. The combination with an automobile top, of a flexible valance depending from the edge of said top, and having a welt along its lower edge, and a curtain having

a trough-like strip of rigid material at its upper edge, the material of said curtain covering said strip, said strip so covered being adapted to engage said welt.

In testimony whereof, I sign this specification.

HORACE T. THOMAS.
